UNITED STATES PATENT OFFICE.

JOHN A. EKELUND, OF MINNEAPOLIS, MINNESOTA, ASSIGNOR TO EKELUND TOY AND NOVELTY COMPANY, OF MINNEAPOLIS, MINNESOTA, A CORPORATION OF SOUTH DAKOTA.

TOY HORSESHOE GAME.

1,113,969.

Specification of Letters Patent. Patented Oct. 20, 1914.

Application filed August 4, 1913. Serial No. 782,816.

To all whom it may concern:

Be it known that I, JOHN A. EKELUND, a citizen of the United States, residing at Minneapolis, in the county of Hennepin and State of Minnesota, have invented certain new and useful Improvements in Toy Horseshoe Games; and I do hereby declare the following to be a full, clear, and exact description of the invention, such as will enable others skilled in the art to which it appertains to make and use the same.

My invention has for its object to provide an improved game apparatus for the playing of the game of quoits or horseshoe, and, to such ends, it consists of the novel devices and combinations of devices, herein-after described and defined in the claims.

In the accompanying drawings, which illustrate the invention, like characters indicate like parts throughout the several views.

Referring to the drawings, Figure 1 is a plan view of the game apparatus; Fig. 2 is a fragmentary section taken on the line $x^2 x^2$ on Fig. 1; Fig. 3 is a section, taken 25 on the line $x^3 x^3$ on Fig. 1; and Fig. 4 is a horizontal section taken on the line $x^4 x^4$ on Fig. 3.

The numeral 1 indicates the game board, which is preferably of rectangular form, 30 and provided with a raised marginal rim 2. At the center of the board is a peg 3 that is surrounded by concentric circles 4 marked on the face of the board or, preferably, on a paper covering 1^a applied to the face of 35 the board.

In each corner of the board there is a mechanical catapult for throwing the horseshoe, or the like, toward the peg 3. These catapults are preferably made in the imitation of toy men having a swinging arm with an expanded hand portion, adapted to receive and hold the toy horseshoe, which latter is indicated by the numeral 5. The body portion 6 of each toy man is preferably made 45 with a single fixed leg, the foot or base of which is bent horizontally and provided with a slot 7 that is enlarged at one extremity to adapt it for application over the head of an anchored stud 8, secured in the 50 board. When the contracted portion of the slot 7 is forced onto the neck of the stud 8, the body of this toy man will be frictionally held with freedom for adjustments around the axis of the said stud for an important 55 purpose, which will hereinafter appear.

To the body of each toy man a leg member 9 is pivoted at 10, the said point 10 being at the shoulder of the body 6. The said pivoted leg 9 has a throwing arm 11, connected thereto by a pivot 12 which pivot is under such tight friction that the said arm will not be accidentally moved in respect to the said leg; but, nevertheless, may be adjusted to different positions by extreme force. The forward movement of the combined leg and arm 9—11 is limited by a laterally bent stop flange 13 on the body 6, which, as shown, engages with the upper front portion of the said leg. The arm 11 is provided with a laterally bent flat end 70 portion 14 having a segmental rear flange 15.

The horseshoe 5 is adapted to be placed on the flat portion of the end 14 and against the rear flange 15. The said laterally bent end portion 14 is much in the form of a 75 shovel, and it is so arranged that in the throwing action it moves edgewise forward and slightly upward, so that the horse shoe, ring, or other form of the quoit will be projected approximately forward toward the 80 peg or target 3, without being caused to turn over. This, as is evident, is an action desired and is such movement as will be given to the quoit when properly thrown by hand.

A coiled impelling spring 16 is attached to a projection of the pivoted leg 9 at its upper end, and, at its lower end, is attached to the horizontally bent foot portion of the fixed leg 6. Preferably, the pivoted leg 9 90 is provided with an extended heel portion 17 that affords a convenient finger piece, by means of which the combined leg and arm 9—11 may be thrown rearward against the tension of the spring 16.

The numeral 18 indicates a counting dial, marked on the board or its covering, and the numeral 19 a coöperating pointer, the latter being pivoted to the board 1 and coöperating with the dial 18 to afford a counter for 100 the points of the game. There should be one of these counters for each man.

When a toy horseshoe 5 is placed on the end 14 of the throwing arm 11, as already described, the throwing of the horseshoe toward the peg 3 is caused by drawing the leg 9 rearward and then suddenly releasing the same, permitting the spring 16 to produce the proper throwing action. The toy throwing man can be given a pivotal adjustment 110

on the stud 8 required to properly aim the throw toward the peg and thus leaving something in this respect to the skill of the operator. The chief skill, however, is in giving 5 the proper retraction to the combined arm and leg so as to thereby propel the horseshoe with greater or less force. Obviously, the greatest point in the game would be to ring the peg 3 by causing the horseshoe to drop 10 around the same. This, however, is not easily accomplished, but skill is required to place the horseshoes inside of the rings 4; and, of course, the closer the horseshoe is thrown to the peg, the more points in the 15 game will be counted by the throw.

The throwing men, as is evident, are not only pivotally adjustable, but are easily detached from the anchored studs 8. For holding the several toy men in compact form laid 20 flat against the board for the purpose of shipment, I apply a holding bar 20 to one of the rims of the board. Preferably, this bar 20 is pivotally attached to the said rim at one end and adapted to be anchored at its 25 other end by a screw 21. When all of the men are laid flat on the board with the foot flanges of the fixed legs 6 clamped between the bar 20 and adjacent rim, the said men will be secured in such compact position with 30 no parts thereof projecting above the rims 2. One of these men is shown as thus applied in Fig. 2.

What I claim is:—

1. In a game apparatus of the kind described, the combination with a board having a peg or target, of a toy throwing man having a fixed leg and a pivoted leg, the said fixed leg being anchored to said board, and the said pivoted leg being under tension to 35 move toward said target, and having a hand portion adapted to hold a horseshoe or the like for projection toward said target.

2. In a game apparatus of the kind described, the combination with a board having a peg or target, of a toy throwing man having a fixed leg and a pivoted leg, the said fixed leg being anchored to said board, and 40

the said pivoted leg being under tension to move toward said target, having a hand portion adapted to hold a horseshoe or the like 50 for projection toward said target, the said hand being capable of pivotal adjustments in respect to the said pivoted leg.

3. In a game apparatus of the kind described, the combination with a board having a peg or target, and a headed stud located at a distance therefrom, of a catapult having a spring pressed throwing member and a relatively fixed body member, the latter having a horizontally bent base portion 60 formed with a slot for interlocking engagement with the said headed stud, the said slot having an enlarged portion adapting it to be applied to and removed from said stud.

4. In a game apparatus of the kind described, the combination with a board having a peg or target, and a headed stud located at a distance therefrom, of a catapult having a spring pressed throwing member and a relatively fixed body member, the latter having 65 a horizontally bent base portion formed with a slot for interlocking engagement with the said headed stud, the said slot having an enlarged portion adapting it to be applied to and removed from said stud, and the said 70 catapult being pivotally adjustable on said stud.

5. In a game apparatus of the kind described, the combination with a board having a raised rim and a clamping bar pivotally 80 attached thereto, of toy throwing men having base flanges for securing them in upright positions to said board and which flanges are adapted to be clamped between said holding bar and the adjacent rim to hold the said 85 men laid down on said board in closely assembled position.

In testimony whereof I affix my signature in presence of two witnesses.

JOHN A. EKELUND.
